UNITED STATES PATENT OFFICE.

FRANK W. CHICKERING, OF HARDWICK, VERMONT, ASSIGNOR OF ONE-HALF TO JOHN J. GALLAGHER, OF HARDWICK, VERMONT.

SAFETY HOLDBACK-IRON.

1,107,898.

Specification of Letters Patent. Patented Aug. 18, 1914.

Application filed April 11, 1914. Serial No. 831,168.

To all whom it may concern:

Be it known that I, FRANK W. CHICKERING, a citizen of the United States, residing at Hardwick, in the county of Caledonia 5 and State of Vermont, have invented certain new and useful Improvements in Safety Holdback-Irons; and I do hereby declare the following to be a full, clear, and exact description of the invention, such as 10 will enable others skilled in the art to which it appertains to make and use the same.

This invention relates to new and useful improvements in hold backs for vehicle shafts, and has for its principal object to 15 provide a device which is permanently secured to and carried by the shafts.

Another object of the invention is to provide a simple and effective means for securing the hold back line and preventing the 20 same from becoming accidentally displaced.

Still another object of the invention is to provide a device which will materially strengthen the shafts and prevent the same from becoming broken.

25 With the above and other objects in view, the invention consists in the novel combination and arrangement of parts which will be fully described in the following specification and accompanying drawings, in 30 which—

Figure 1 is a side view of a shaft showing the hold back iron in place. Fig. 2 is an enlarged detail view in perspective of the hold back attachment, and Fig. 3 is a side view 35 of the device showing the method of assembling.

Referring now to the drawings by characters of reference, the numeral 1 designates a horse which is standing between the 40 shafts 2. A portion of the harness is designated generally by the numeral 3 and is provided with the usual hold back straps 4, which surround the hook in the usual manner and are secured by means of the buckle 45 or similar fastening means 5.

The hold back attachment is designated generally by the numeral 6 and comprises the base plate 7 which is provided with a plurality of screw receiving apertures 8. A 50 longitudinal slot 9 is formed in the base

plate 7 near one end and the metal between the lateral extremities of the slot 9 and the lateral edges of the plate 7 is preferably bent upwardly as illustrated at 10, the use of which will be more fully hereinafter described. A suitable hook-shaped body portion 11 is secured to the plate 7 near the end opposite the slotted end and is arranged to form the hook 12 which prevents the hold back straps 4 from becoming displaced. 60 A suitable leaf spring 13 is screwed or otherwise secured as at 14 to the plate and is bowed upwardly to conform to the shape of the hook as clearly shown in the drawings. The free end of the spring 13 extends 65 downwardly as illustrated in Fig. 2 and is provided with the upwardly curved extension 15 which is arranged to form the tongue to permit the hold back strap to be easily placed in position when the device is 70 in use. The point where the spring 13 and the tongue meet is arranged to lie in the slot 9 and thereby prevent the strap from becoming accidentally removed.

It will be apparent from the foregoing 75 that in use the hold back strap is passed around the hook as shown in the drawings and the free end thereof is secured by means of the buckle 5. It will be evident that when the strap 4 is against the hook 11 and 80 backward pull is exerted against the strap that the pull will be transmitted to the hook and thereby affect the shaft. In case of a runaway should the traces or tugs break it will be apparent that the hold back will be 85 released as the strap will pass between the plate 7 and the free end of the spring 13 and thus hang free from the shafts, thereby releasing the horse from the vehicle.

While in the foregoing there has been 90 shown and described the preferred embodiment of this invention, it is to be understood that such changes may be made in the combination and arrangement of parts as will fall within the spirit and scope of the invention as defined in the appended claim.

Having thus described my invention, I claim:

A device of the character described comprising a base plate provided with a slot 100

near one end, metal between the slot and the lateral edges of the base plate being bowed upwardly, a hook member secured to the base plate near the end opposite the slot, 5 and a bowed leaf spring secured to the base plate near the hook member and overlying the same, the free end of said spring lying in direct alinement with the slot and there-

by being prevented from being accidentally displaced.

In testimony whereof I affix my signature in presence of two witnesses.

FRANK W. CHICKERING.
